DESIGN FOR A COMBINATION PIANO AND XYLOPHONE UNIT

Benjamin F. Jay, New York, N. Y., assignor to William Jay Emanuel Co., New York, N. Y., a partnership composed of Benjamin F. Jay, Robert Emanuel, and William J. Emanuel

Application November 8, 1946, Serial No. 134,624

Term of patent 3½ years

(Cl. D56—9)

To all whom it may concern:

Be it known that I, Benjamin F. Jay, a citizen of the United States, residing in New York city, county, and State of New York, have invented a new, original, and ornamental Design for Combination Piano and Xylophone Unit, of which the following is a specification, reference being had to the accompanying drawing, forming a part thereof, in which:

The single figure is a perspective view of my new design of combination piano and xylophone unit.

The design of the rear portion of the device is substantially plain and unornamented.

I claim:

The ornamental design for a combination piano and xylophone unit, as shown and described.

BENJAMIN F. JAY.
